BRAIDING MACHINE

Howard A. Elliott, Highland Park, Mich., assignor
to Essex Wire Corporation, a corporation of
Michigan

Application June 22, 1931, Serial No. 545,896

7 Claims. (Cl. 96—3)

My invention relates to improvements in braiding mechanism and more particularly to mechanism for braiding determinate lengths of material.

In covering various kinds of wires, insulated conductors and cords, it is a well known practice to braid a covering of textile material tightly about the wires by the use of machines especially designed for that purpose and well known in the art as textile braiders. One common type is what is known as the Wardwell braider in which textile supplies are braided at a relatively high rate of speed about the wire strand or conductor to be covered. In certain wiring arrangements it is often desirable to cover two or more insulated wires with a protective covering to form a cable of certain and determined length, that is, make it up in pieces for use, for example, in hooking up various electrical and ignition systems in automotive vehicles. These coverings should be of the same length and should have certain characteristics such as leaving uncovered the end portions of the wires and, in many instances, allowing one or more of the wires to protrude from a portion of the covering intermediate the ends thereof to form side leads. In the ordinary forms of braiding mechanism no provision is made for incorporating additional conductors, nor for predetermined desired lengths of the assembly of conductors, nor for taking out side leads from the assembly.

An object of my invention is to provide an improved method for braiding determinate lengths of textile coverings about a plurality of conductors for forming cables.

Another object of my invention is to provide improved means for determining the length of covering to be braided on a plurality of wires to form certain lengths of cables.

Another object of my invention is to provide visible means for indicating when a predetermined length of cable has been braided.

Yet another object is to provide an adjustable indicator for measuring the desired amount of braiding which may be readily reset to facilitate the braiding of pieces of various lengths.

Still another object of my invention is to provide improved means for maintaining a fixed braiding point and facilitating manipulation of the wire below the braiding point.

A further object of my invention is to provide an improved method of leading conductors outwardly through the side of the braided covering.

A further object is to provide apparatus for indicating the point at which the intermediate side

leads are to be formed which apparatus is readily adjustable.

A still further object of my invention is to provide an improved means of introducing the conductors to be covered to the braiding mechanism.

Further objects and advantages will become apparent throughout a reading of the following detailed description and accompanying drawings, in which—

Figure 1 is a fragmentary perspective view of a braiding machine incorporating the improvements of my invention.

Fig. 2 is an enlarged perspective view of the improved braiding ring of my invention.

Fig. 3 is an elevation of a cable formed by the method and on the apparatus of my invention.

Fig. 4 is an enlarged detailed side view of the measuring and indicating device of my invention.

Fig. 5 is an enlarged front elevation of the device illustrated in Fig. 4.

Fig. 6 is an enlarged elevation of a modified form of cable, and

Fig. 7 is an enlarged detailed view of a chain and hook securing device employed in the apparatus of my invention.

Referring now to the drawings in detail, in which like numerals designate like parts throughout the several views, I have shown in Fig. 1 a textile braiding machine 10 of any well known design, such, for example, as those well known in the art as Wardwell braiders. This machine has two tiers of yarn supports 11 or supply cops, each driven in an opposite direction to the other by a pulley driven shaft 12 connected with some suitable source of power (not shown). These yarn carriers have lenticular shaped decks 13 resembling shuttles which weave or braid the lines of yarn under and over alternate adjacent lines as the two tiers of supply cops are rotated in opposite directions.

The lines of yarn are all drawn to a center braiding point and engage and pass over a braiding ring 15 shown in Fig. 2 which has an annular base 16 with an aperture 17 therein through which the wires to be covered pass. An upright arm 18 is secured in the base 16 and extends vertically upward therefrom to support the ring 15 at its upper end. The ring 15 is of smooth and rounded external contour to facilitate passage of the braided yarns as they are drawn over its outer surface as illustrated in Fig. 1. The base 16 is secured to the central housing of the braiding machine 10 by bolts 19 or other suitable fastening devices. This braiding ring differs from other devices previously employed to maintain

the braiding point in that it provides ready access to the wires or material being covered below the braiding point. The space between the ring 15 and its supporting base is unrestricted except for the narrow vertical support arm and the operator has ready access to the wires being braided for a space considerably below the braiding point. This facilitates manipulation and treatment of the ends of the wires when forming cables of determinate lengths and forming side leads as will hereinafter be described in detail.

The measuring and indicating mechanism of my invention is applied to the braiding machine and driven through a suitable chain of gears and power transmission devices, by the same source of power that drives the braider, as best shown in Figs. 4 and 5.

A horizontally disposed drive shaft 21 is rotatably journaled in suitable bearings formed in the upper portions of supporting arms 22 and 23 of the frame of the braiding machine 10. A sprocket gear 24 is fixed at one end of the shaft 21 and is driven by a chain 25 which is operatively connected with the drive shaft 12 of the braider by a system of gearing and is driven thereby. The shaft 21 is therefore rotated at a fixed rate relative to the rotation of the braider 10. Suitable reduction gearing may be employed to obtain the desired speed of rotation of the shaft 21 in proportion to the rate at which the braider rotates. It will be very much slower than that of the braider ordinarily. A gear 28 is carried by a shaft 29 which is rotatably journaled in a suitable manner in a bearing block 30 attached to the upper end of the main support arm 23. A measuring drum or take up reel 31 is fastened to the gear 28 by bolts 32 or other suitable fastening devices and rotates therewith. The gear 28 is in mesh with a pinion gear 34 fixed on the shaft 21 and driven thereby. The ratio of these gears is such that the measuring drum 31 will rotate considerably slower than the shaft 21.

The measuring drum 31 is preferably made of light metal and the surface is slotted axially to provide a plurality of evenly spaced prongs 35 with slots 36 intervening between each of the prongs. These prongs are slightly tapered towards the open end of the drum to facilitate removal of the braided pieces of cable as will hereinafter be described.

An indicator 38 is provided to designate the points at which certain operations are to be performed on the wires and braid in making up the wiring assembly. This indicator includes a flat metal frame 39 the upper part of which is vertically disposed and the lower part of which is arcuately shaped to conform to the shape of the drum 31. The frame 39 is mounted in position at its lower end by a bracket 40 which is secured to the frame member 23 and at its upper end by a bracket 41 which is fastened to the bearing block 30 by suitable fastening devices. An elongated central slot 43 extends throughout the length of the frame 39 intermediate its edges as best shown in Fig. 5.

A horizontally disposed pointer 44 extends over the drum 31 and is adjustably mounted on the frame 39 for vertical movements by a suitable thumb screw and lug fastening device 45 which passes through the slot 43. Such fastening devices are well known and are of the type which when loosened will allow the pointer 44 to be slid upwardly and downwardly on the frame 39 so that it may thus be set in any desired position

by tightening of the thumb screw. The pointer 44, it will be noted, extends parallel to the prongs and slots of the drum 31. A second pointer 47 is adjustably mounted in the slot 43 of the frame 39 above the bracket 41 by a fastening device 48, similar to the fastening device 45 just described. The pointer 47 has a downwardly depending and rearwardly extending point 49 and may be set in any desired position by a tightening of the fastener.

A metal bracket 51 is mounted on the gear box 30 and extends over the drum at the upper and rearward side thereof and is set relatively close to the drum to act as a guide for the rows of cable being wound on the drum and as a safety guard to prevent the cable from being started too close to the gear 28 or from being wound in that direction. The member 51 also acts as an indicator of the rows being wound on the drum.

A feed pipe 53 is provided at the underside of the braider to facilitate the proper introduction of the material being braided into the machine. Side pipes or tubes 54 and 55 are provided at each side of the pipe 53 to accommodate various pluralities of wires being braided. The central feed pipe 53 is relatively larger than the side pipes 54 and 55 so that a larger cable 72 such as illustrated in Fig. 6 may be passed through this central pipe and side wires fed through the side pipes 54 and 55 when forming this type of wiring assembly.

A chain 57 having a hook 58 at its upper end and a hook 59 at its lower end is provided. The upper hook 58 is adapted to engage the prongs 35 of the drum 31 and the lower hook 59 is pointed to engage the textile braid.

My invention is particularly useful in making up wiring assemblies which must be of a predetermined relatively short length, for example, of 2, 4, 6, 8 feet or other determinate lengths, and having the ends of the wire extending beyond the braided covering at each end, also in forming side leads from one or more of the wires. Such a wiring assembly as may be readily formed by my improved apparatus is shown in Figs. 3 and 6.

To form the cable shown in Fig. 3 the operator proceeds as follows: A pair of insulated wires 60 and 61 are drawn from reels 62 and 63 respectively which are rotatably mounted in some suitable manner in frames behind the braiding machine 10. The wire 60 is fed through the side tube 54 and the wire 61 through the side tube 55 and passed upwardly through the braiding machine, or through the aperture 17 in the base 16 of the braiding ring 15 then upwardly through the center of the braiding ring 15. The braiding machine is threaded and the hook 59 of the chain 57 engages the braid 65 which is formed in a loop 66 to facilitate engagement of the hook 59 of the chain. The upper hook 58 of the chain is engaged with a prong 35 preferably in alignment with the indicator 44 or at some other predetermined point. The operator also takes care to engage the hook 58 in alignment with the point 49 of the indicator 47. The upper ends of the wires 60 and 61 are drawn upwardly above the braiding point a distance equal to that which they are required to protrude and the braiding machine is then started in operation. A covering of textile braid 65 will be woven tightly about the wires 60 and 61 and the drum 31 will act as a take up reel and revolve in the direction indicated by the arrow in Fig. 4, winding the chain 75

and associated cable which is being formed about the surface of the drum 31. The member 51 acts as a guide to prevent winding of the rows of cable upon the drum toward the gear or beyond 5 a predetermined point. The operator then watches the rows of cable with respect to the pointer 49 which are being wound upon the drum and when a certain number of rows have been wound, which amount is determined by the length 10 of wiring assembly desired, one of the wires may be looped and extended outwardly from the assembly to form a side lead. To accomplish this result the machine is stopped as the chain arrives at a point opposite the indicator 44 and the 15 wire 61 may be pulled up the required distance through the tube 55 to form the side leads and the braiding machine may then be restarted to continue to braid the covering upon the assembly, the operator holding the side lead 61 out 20 horizontally for a moment as it passes the braiding point and the cover will be braided at 70 around the side lead 61.

It will be noted that this operation is facilitated by the employment of the braiding ring 16 of 25 my invention. Since the braiding point will be maintained at a point slightly above the braiding ring 15 the wires 60 and 61 which are passing through the opening 17 in the base of the braiding ring and the braiding ring itself will be exposed and accessible below the ring 15 and either one may be pulled outwardly between the yarns of the braiding machine and held there until this point has been braided around. The wires 61 may then be cut to form short leads as those illustrated in Fig. 3 or finished in any other desired manner. This cutting may be done by the operator as the braiding machine continues to braid the covering on the lower part of the assembly. When the side leads 61 reach the drum the operator 30 may twist them around one of the prongs 35 by inserting them into one of the grooves 36 therebetween, as illustrated in Fig. 5. The braiding operation then continues under the observation of the operator until a required number of 35 additional rows have been wound about the take up reel 31 as indicated by the side lead wires 61 having been rotated to a point opposite the pointer 44, as illustrated by the dotted lines in Fig. 5. The machine may then be stopped and 40 the operator may cut the wires 60 and 61 below the braiding point and braiding ring 15 the required distance that it is desired for them to protrude. The wires are then held outwardly by the operator and the machine restarted and 45 run a short distance beyond this point which is the bottom of the braid. Since the wires 60 and 61 will be held outwardly from the braiding point the yarn will be twisted about itself and the machine will braid a tail piece which will 50 preserve the braiding point. The finished cable may then be removed from the take up reel 31 by a second chain 57 may be hooked upon the prong 55 of the take up reel 31 by means of its hooked end 58. The braided tail piece is then bent around the lower hook 59 of the chain 57 to form a loop 60 illustrated in Figs. 3 and 6 and the ends of the wires 60 and 61 moved upwardly the required distance above the braiding point and the braiding operation resumed to form another braided cable in manner similar to that described.

It is readily apparent that the pointers 44 and 49 may be adjusted to indicate any desired length of assembly and any desired spacing of the side leads intermediate the ends of the assembly.

The operator may rely upon the upper or lower ends of the chain or the point of taking outside leads as desired to count the revolutions upon the take up reel which are necessary to be made before the required length of assembly has been formed. It is also apparent that any desired combination of lengths or relative indications may be made by so adjusting the indicator. The indicator 49 for example might indicate the point at which the machine was to be stopped for the 10 completion of the assembly while the indicator 44 might be employed to indicate the point at which the machine is to be stopped to take out the side leads. For example, it might be found that one and one-half turns would bring the upper end of the braid or the point at which the hook 59 engages the loop 66 directly opposite the indicator 44 which will be the point at which the side lead is to be made, or it may require one and three quarters revolutions or two whole revolutions. The adjustable indicators of my invention may be readily adapted to any changes of 15 lengths and combinations.

An assembly such as illustrated in Fig. 6 may be braided in a similar manner as that described 20 by passing the braided center portion 72 through the large center pipe or tube 53 and the side wires 60 and 61 through the side tubes 54 and 55 respectively.

The employment of the improvements of my 25 invention in braiding cables of determinate lengths results in speed of operation, uniformity of result, and ease and economy in the manufacture of such cable.

Formal changes may be made in the specific 30 embodiment of the invention described without departing from the spirit and substance of the broad invention, the scope of which is commensurate with the appended claims.

I claim:

1. A method of covering wires to form determinate lengths of cables having the wires protruding beyond the cover at each end, and forming side leads intermediate the ends of said cover which consists in passing a plurality of wires through a textile braiding machine having a fixed braiding point, extending the ends of said wires upwardly above said braiding point, then braiding a predetermined length of covering upon said wires downwardly from this point, drawing out one of the wires and holding it to one side of the braiding point to form a side lead, running the machine to braid a further cover upon said wires past said side lead for an additional predetermined distance, cutting off the wires below 45 said braiding point, bending said wires outwardly away from said braiding point to prevent further covering, running the machine to braid a short tail between the wires beyond the point at which the wires are bent and cutting off the braided tail at the point where the wires are bent.

2. In a device to assist in determining the length of braids formed by a power driven braiding machine, a rotatable drum, a braid wound about said drum, a stationary frame positioned at right angles to the axis of rotation of said drum, indicators on said frame extending over the surface of said drum and means driven by said braiding machine to rotate the drum relative to the indicators at a fixed rate definitely proportionate to the speed of operation of the braiding machine.

3. In a device for assisting in determining the length of braids formed by a power driven braid-

ing machine, a rotatable drum driven by said machine at a rate fixed definitely proportionate to the speed of operation of said machine, a braid attached to said drum and adapted to be wound thereabout, a stationary indicator frame positioned in front of said drum and visible indicators on said frame extending over the surface of said drum to facilitate the counting of the revolutions of said drum.

10 4. A device for assisting in determining the length of braid formed by a power driven braiding machine, a rotatable drum positively driven by said machine and adapted to wind the braid in rows above the periphery of the drum, a stationary indicator frame positioned adjacent said drum and provided with a circumferentially directed member, an arm slidably secured to said member for adjustment circumferentially of the drum, and a second member provided with an 15 arm slidably secured thereto for adjustment tangentially of said drum.

10 5. A device for assisting and determining the length of braid formed by a power driven braiding machine, a rotatable drum positively driven by said machine and adapted to wind the braid in rows about the periphery of the drum, a stationary indicator frame positioned adjacent said drum, a member extending circumferentially about said drum and provided with an arm 20 slidably secured thereto for adjustment circumferentially of the drum, a second member provided with an arm slidably secured thereto for adjustment tangentially of said drum, and a stationary guard member provided on said machine

and extending over the surface of the drum in close proximity thereto to prevent winding of the rows beyond a predetermined point.

6. In a device for assisting in determining the length of braid formed with a power driven braiding machine, a rotatable drum positively driven by said machine and adapted to wind the braid in rows about the periphery of the drum, a stationary indicator frame positioned adjacent 10 said drum, a circumferentially directed member provided with an arm slidably secured thereto for adjustment circumferentially of the drum, a second member provided with an arm adjustable tangentially of said drum, a stationary guard member mounted on said machine and extending 15 over the surface of the drum in close proximity thereto to prevent winding of the rows beyond a predetermined point, and an attaching device adapted to connect the braid to the drum so as to 20 wind said braid thereon.

7. The method of covering wires to form a length of cable having wires projecting through the cover intermediate the ends thereof to form side leads, which method comprises passing a plurality of wires through a textile braiding machine having a fixed braiding point and braiding a length of cover upon all of said wires, drawing out and holding to one side of said braiding point a loop including certain but not all of said wires, 25 braiding a further length of cover upon all of 30 said wires, and cutting said loop to provide side leads.

HOWARD A. ELLIOTT.
